UNITED STATES PATENT OFFICE.

JULIUS KRUTTSCHNITT, OF NEW CANAAN, CONNECTICUT; E. MINNA KRUTTSCHNITT EXECUTRIX OF SAID JULIUS KRUTTSCHNITT, DECEASED.

RAILWAY TIE PLATE.

Application filed August 26, 1924. Serial No. 734,275.

To all whom it may concern:

Be it known that I, JULIUS KRUTTSCHNITT, a citizen of the United States, residing at New Canaan, in the county of Fairfield and State of Connecticut, have invented certain new and useful Improvements in Railway Tie Plates, of which the following is a specification.

This invention relates to a construction 10 for railway tie plates and has for its chief object a novel combination of structural features contributing to produce an efficient tie plate combining the functions of an adequate rail support and a rail anchor serving 15 to resist and check longitudinal creeping of the rail.

In carrying out that object the invention has in view to utilize and conserve all of the desirable and practical features of the invention of my application for Letters Patent 20 Serial No. 725058 filed July 9, 1924, and to combine with such features novel means for obtaining a scientific reinforcement of the plate structure throughout, and 25 definitely to provide means whereby the rail may be efficiently locked to the tie plate, to prevent creeping, by the driving of the spikes through the tie plate and into the tie.

With these and other objects in view which 30 will more readily appear to those familiar with the art as the nature of the invention is understood, the same consists in the novel construction, combination and arrangements of parts hereinafter more fully described, illustrated and claimed.

A practical form of the invention is shown in the accompanying drawing, in which—

Figure 1 is a top plan view of an anti-creeper tie plate construction, embodying 40 the improvements contemplated by the present invention.

Figure 2 is an end view of the improved tie plate.

Figure 3 is a vertical cross sectional view 45 of the tie plate on the line 3—3 of Figure 1, showing a rail in position on the plate and held locked thereto through the action of the track spikes.

Figure 4 is a cross sectional view of the 50 new plate construction, the section being taken on the line 4—4 of Figure 1.

Figure 5 is a side edge view of the plate, 55 showing the same from that side provided with the upstanding reinforced clamping hooks.

The embodiment of the invention shown in the accompanying drawings includes in its general organization a plate body designated by the numeral 1, preferably of rectangular form, and for the purposes of good designing and the avoidance of sharp angles or points, the same may be provided with the rounded corner portions 2, which also eliminate unnecessary metal at the corner locations. This plate body may be shaped 60 from the metal according to any of the well known processes for making tie plate structures, and the same is provided with a flat or substantially flat tie seating bottom face 2^a from which project a pair of oppositely 70 located parallel tie engaging, downwardly projecting, ribs 3 and 4. These ribs have a shallow depth from the bottom of the plate and are formed blunt with no sharp edges or projections in order that the seating of the plate on the tie will be by compression, instead of by cutting into the 75 fibres of the wood as is common with many types of tie plates now in use.

At its upper side the plate body 1 is 80 formed with a flat or substantially flat rail supporting seat 5 preferably inclined downwardly and inwardly, and preferably interrupted by the longitudinally extending grooves 6. This top rail seat extends from 85 end to end of the plate body, and is preferably sufficiently wide to accommodate the bases of more than one rail section, thus enlarging the usefulness of the tie plate, and 90 contiguous to the outer and inner edge portions of the rail seat the plate body is pierced by the outer and inner spike openings or slots 7 and 8 respectively. These are arranged in the usual staggered order 95 thereby to obtain the best spiking results. Also it will be observed, as pointed out in said application, that the spike slots or 100 openings preferably are arranged in the vertical plane of the bottom ribs 3 and 4 on the plate body, so that the plate is not weakened in any way at the locations of the spike slots or openings.

In carrying out the plan of reinforcement for the plate body, and to provide for holding it in place, the same is formed at 105 its ends with the downwardly projecting girder flanges 9. In the present design of the plate body the said depending girder flanges 9, at the ends of the body, are preferably of a crescent or downwardly arched 110

form, and the length of these flanges is of less extent than the width of the plate. In other words the depending flanges 9 extend across the ends of the plate body between 5 and slightly beyond the tie engaging compression ribs 3 and 4 with the result of substantially stiffening the end portions of the plate where the reinforcement is most desirable and it will be observed that toward 10 the outer edge of the plate body the girder flanges 9 project beyond the outer edge of the rail seat to give greater stiffness and strength to that part of the plate through which the resultant of the applied forces 15 usually passes. The flanges 9 project sufficiently below the bottom of the plate body to engage well over the sides of the tie, thus acting, in addition to their reinforcing function, as abutments and holding means which 20 prevent the tie plate from moving longitudinally, that is transversely of the tie.

An important and distinguishing feature of the present invention is the provision of the means for locking the rail against creeping, such means being rendered effective through the action of the spikes. Referring more particularly to that phase of the invention it is to be observed that the tie plate body is provided on the upper side thereof, 25 and contiguous to the outer edge of the rail seat 5, with a plurality of upstanding clamping hooks 10, which preferably alternate with the outer spike holes or slots 7. These hooks are in the form of lugs or shoulders rising from the top of the plate and formed at their edge portions with vertically disposed reinforcing flanges 11 which give stiffness and strength thereto and each 30 of said hooks is provided with an inclined engaging lip 12 which is disposed above and overhangs the outer edge portion of the rail seat 5. The said lip is adapted to be frictionally engaged by the outer flange of the rail when such flange is forced into the 35 hooks by the pressure of the track spikes when driven through the inner spike holes or slots 8 against the inner flange of the rail.

Preferably the inner spike holes or slots 40 50 55 8 are arranged diametrically opposite the clamping hooks 10, one of the holes or slots being directly opposite one of the clamping hooks. And, at what may be termed the outer side of each of the inner spike holes or slots 8, the plate body is provided with an upstanding lug 13 constituting a spike

abutment, and this lug is stiffened and braced by an integral gusset 14 formed on the plate body between an edge portion thereof and the outer side of the upstanding lug 13. The inner bearing face 15 of each lug 13 is preferably inclined to facilitate and guide the movement of the spike through the hole or slot 8, and serving to crowd the spike with great force against the inner flange of the rail when the inside spikes are driven home into the tie. The result of this movement of the spikes is to forcibly crowd the outer rail flange into the tapering spaces provided by the overhanging clamping hooks 10. Consequently anti-creeping of the rail will be checked and prevented by the friction of the spikes against the edge of the rail base, by the friction of the outer rail flange within the clamping hooks 10, and by the clamping action of the spike heads on the rail base.

From the foregoing it is thought that the construction, functions and advantages of the herein-described anticerper tie plate structure will now be apparent, and it will be understood that minor changes in the form, proportion and details of construction may be resorted to without departing from the spirit or sacrificing any of the advantages of the invention.

I claim:

1. A construction for tie plates including a body provided at its upper side with a rail seat and at its lower side with a pair 90 of tie compression ribs of shallow depth which are spaced apart to a distance corresponding at least to the width of the rail seat, said body being further provided at its end edges with depending outwardly arched 95 girder flanges approximately coextensive in length with the width of said rail seat and adapted to engage over the sides of the tie.

2. A tie plate structure including the plate body provided with alternating spike holes and upstanding clamping hooks contiguous one edge portion of the rail seat, other spike holes contiguous the other edge portion of the rail seat and disposed opposite the clamping hooks, and upstanding 100 spike abutments projecting above the plate body at the outer sides of said other spike holes.

In testimony whereof I hereunto affix my signature.

JULIUS KRUTTSCHNITT.
